UNITED STATES PATENT OFFICE.

CHARLES A. PIERSON, OF NEWARK, NEW JERSEY, ASSIGNOR TO FREDERICK H. LARTER, HARRY C. LARTER, AND HALSEY M. LARTER, OF SAME PLACE.

BUTTON FOR SHIRTS, &c.

SPECIFICATION forming part of Letters Patent No. 667,574, dated February 5, 1901.

Application filed January 3, 1899. Serial No. 700,914. (No model.)

To all whom it may concern:

Be it known that I, CHARLES A. PIERSON, a citizen of the United States, residing at Newark, in the county of Essex and State of New Jersey, have invented certain new and useful Improvements in Buttons for Shirts, &c.; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to certain improvements in that class of shirt-buttons represented by the one shown in Patent No. 616,057, dated December 13, 1898, the objects of the present improvements being to secure increased spring accommodation and a longer projection for a certain "piston" or sliding shoe-section, and thereby enable the button to be employed with greater security not only in shirts having the usual eyelets for studs, but also in shirts having the ordinary long buttonholes, and to secure other advantages and results, some of which may be referred to hereinafter in connection with the description of the working parts.

The invention consists in the improved button for shirts, &c., and in the arrangements and combinations of parts of the same, all substantially as will be hereinafter set forth, and finally embraced in the clauses of the claim.

Referring to the accompanying drawings, in which like letters of reference indicate corresponding parts in each of the several views, Figure 1 is a side elevation of the improved stud. Fig. 2 is a longitudinal section of the same on an enlarged scale. Fig. 3 is a transverse section taken at line x, Fig. 2; and Fig. 4 is a detail view of the sliding shoe-section and spring detached from the head and shank of the button.

In said drawings, a indicates the head of the button, which may be ornamental or plain or may furnish a setting for a stone or jewel in any ordinary manner.

b indicates the shank, fastened to the inner

side or back of the head by soldering or any other means common in the jeweler's art and comprising a hollow wire bent at right angles at a point a little back from the head to form a barrel b' and post b², the said post supporting the head and said barrel lying in a plane substantially parallel with the plane of the head, as will be understood, and the bend being suitably rounded or curved. At said bend in the shank the latter is open at the outer side, as at b², Fig. 2, the opening being of a size adapted to permit the outpassage therethrough of a sliding hollow section c, the said opening being axially in line with the barrel b' of the shank. The section c when projecting, as shown in Fig. 2, taken in connection with the barrel b', forms a shoe for the button, which cooperates with the head in holding the overlapping portions of the garment together, as will be understood. The said sliding shoe-section c is of a diameter substantially equal to the diameter of the interior chamber of the barrel b' and is thus adapted to slide in said barrel with a positive movement. The inner end of the section c is open, while the outer end is partly closed, a small opening being formed therein in the preferred construction to receive the end of a rod d, the said rod carrying exteriorly thereon a spring e. The said rod d is fastened to the closed outer end of the section c, being reduced to form a shoulder d² to engage the inner side of the section c at the end thereof, the reduced portion of the rod fitting the perforation and being adapted to be upset at the extremity to form a head d³, whereby the said rod d is firmly fixed to the section c. I may employ any other method of fastening the rod to the section as convenience, circumstances, or conditions may dictate. The said rod d is considerably longer than the section c and extends longitudinally therethrough and out into the barrel b' and through the same, the said barrel being also partly closed at its projecting end and provided with a small perforation of sufficient size to allow the outpassage therethrough of the said rod d. At or near its extremity the said rod is provided with a peripheral groove d' and thereat re-

ceives a conical end cap *f*, the said cap being of sheet metal shaped or formed at its base, as at *f'*, so as to enter the said peripheral groove under pressure and be firmly fixed to the rod. The said conical cap *f* forms a finger-knob and is pointed at its outer extremity to facilitate its passage through the button-hole, and at its base is made broad to permit of easy grasping by the hand, the said cap serving as a finger-piece by means of which the rod may be drawn lengthwise through the barrel against the power of the spring *e*. The outer movement of the rod when thus drawn by the fingers against the spring is limited by the engagement of the inner end *d⁴* of the section *d* with the end walls *d⁵* of the barrel, the interior end of the barrel *c* being sufficiently open to allow the free passage of the spring *e* therethrough. The spring *e* is thus permitted to bear at one end against the end walls at the closed projecting end of the section *c* and against the interior end walls *d⁵* at the oppositely-projecting end of the barrel. I thus am enabled to employ a spring of considerable relative length, and, furthermore, am enabled to employ a section *c* of considerable projection when in its normal projecting position, and thus the shoe as a whole may be given increased length and the button secured within an ordinary buttonhole without liability of escape.

While I have shown one way of constructing the improved button, it is evident that the same may be modified in the construction without departing from the scope and spirit of the invention, and therefore I do not wish to be understood as limiting myself by the positive descriptive terms herein employed, excepting as the prior state of the art may require. Furthermore, I may dispense with the head of the button and furnish the market with the spring-back, comprising the L-shaped tubular main part, consisting of a barrel and post, to which the head may be fastened by the person purchasing the said spring-back, the tubular sliding shoe normally forming a prolongation of the barrel and the spring being inserted in the barrel and sliding shoe, on a stem fastened to said sliding shoe, all in the manner already sufficiently described.

Having thus described the invention, what I claim as new is—

1. A button comprising a head, a shank having a post connected to said head and a tubular barrel disposed at right angles to said post or approximately so, said barrel having one end, where it connects with the post, open, and the other end also open and provided with a bearing for a spring, a hollow shoe-section slidably arranged in said barrel

and serving as a casing for a spring, said slideable shoe-section having its end toward the post end of the barrel provided with a spring-bearing, a stem or rod in said shoe section or casing secured to said casing at the bearing therein for the spring and extending from said spring-bearing out from the barrel at or near the spring-bearing of said barrel, and a spring encircling said rod or stem and having one portion resting within the slideable shoe section or casing against the bearing within the same, and the remaining portion of the spring, in its normal position, projecting from said casing into the barrel and resting against the spring-bearing thereof, substantially as set forth.

2. A button comprising a head, a post connected therewith and a tubular barrel at a right angle to said post, or approximately so, said barrel having one end, where it connects with the post, open, and the other opposite end also open and provided with a spring-bearing, a hollow or tubular shoe section or casing slidably arranged in said barrel, having one end closed and interiorly providing a spring-bearing, a stem or rod in said barrel, secured at one end to said closed end of the shoe section or casing and having the other end projecting through the barrel and through the open end of said barrel having the spring-bearing, a knob on said stem or rod, and a spring having one end resting against the spring-bearing within the slideable shoe section or casing, and one portion of said spring arranged in said casing and the remaining portion of the spring in its normal position projecting from said shoe-section into the barrel and resting against the portion of the barrel having the spring-bearing, substantially as set forth.

3. As a new article of manufacture, a spring-back for a button or stud, composed of an angular part of bent tubing comprising a post and barrel, the latter having a spring-chamber and a spring abutment or bearing therein, a tubular sliding shoe forming normally a prolongation of said chamber and having a closed end opposed to said abutment, a long spiral spring inclosed within said chamber and shoe, and a stem within said spring attached at one end to said closed end of the shoe and provided at its other extremity with a knob protruding from the barrel, substantially as set forth.

In testimony that I claim the foregoing I have hereunto set my hand this 20th day of December, 1898.

CHARLES A. PIERSON.
